(No Model.)

J. S. GRIFFIN.

MACHINE FOR DRAWING BARS.

No. 293,450.

Patented Feb. 12, 1884.

UNITED STATES PATENT OFFICE.

JOHN S. GRIFFIN, OF CLEVELAND, ASSIGNOR TO HIMSELF AND MATHEW BOLEYN, OF NEWBURG, OHIO.

MACHINE FOR DRAWING BARS.

SPECIFICATION forming part of Letters Patent No. 293,450, dated February 12, 1884.

Application filed April 18, 1883. (No model.)

To all whom it may concern:

Be it known that I, JOHN S. GRIFFIN, of Cleveland, Cuyahoga county, and State of Ohio, have invented a new and Improved Machine for Drawing Bars for Heavy Shafting, of which the following is a full, clear, and exact description.

The object of my invention is to provide a new and improved machine for drawing iron and steel bars for heavy shafting in one continuous operation.

Reference is to be had to the accompanying drawings, forming a part of this specification, in which similar letters of reference indicate corresponding parts in all the figures.

Figure 1 is a longitudinal elevation of my improved machine for drawing bars for heavy shafting. Fig. 2 is a cross-sectional elevation of the same on the line $x x$, Fig. 1. Fig. 3 is a longitudinal elevation of the bar, showing the arrangement of the dies on the same. Fig. 4 is a plan view of the sliding carriage for holding the end of the bar. Fig. 5 is a plan view of a modification of the same. Fig. 6 is a front end elevation of the same. Fig. 7 is a longitudinal elevation of the same. Fig. 8 is a plan view of the gate-bar for holding the die-blocks in place. Fig. 9 is a longitudinal elevation of a die-block provided with two dies. Fig. 10 is a cross-sectional elevation of the same on the line $y y$, Fig. 9. Fig. 11 is a front elevation of the die-block, containing a suitable die.

A frame, A, is constructed with a horizontal track, A', on which the carriages B can slide, in which carriages the end of the bar to be drawn is held. A longitudinal driving-shaft, C, is journaled in suitable standards at the side of and parallel with the frame A, and projects beyond the end of the machine, which shaft is rotated from a suitable motor by means of suitable appliances. Near each end of the shaft C a beveled cog-wheel, C', is mounted loosely thereon, which is provided on one side with beveled teeth and on the opposite side with a notched clutch-wheel, C'', adapted to engage with a sliding clutch-wheel, C'. This latter wheel C' is secured on the shaft C in such a manner that it must rotate with the same, but can slide longitudinally, which slid-

ing clutch-wheel C' is provided with an annular groove, into which a bifurcated prong, d, passes. Said prong is formed on the lower end of a centrally-pivoted lever, D, pivoted to the frame A, which lever D has its top and bottom ends connected by connecting-rods d' and d'', respectively, with a series of like levers, D'. These levers D' are pivoted centrally near the middle of the frame A, and are connected by rods d', and provided with upwardly-projecting handles D'', so that if one handle D'' is swung in one direction or the other the levers D and D' will be swung in the same direction, and will all be operated simultaneously. The loose-beveled cog-wheel C' engages with a beveled cog-wheel, E, mounted on one end of a transverse shaft, E', on the opposite end of which a pinion, E'', is mounted rigidly, which pinion engages with a large cog-wheel, F, mounted on a transverse shaft, F', journaled in the frame A, near one end of the same. On this shaft F' a sprocket-wheel, F'', is rigidly mounted, over which a chain, G, passes, which is coupled to one of the sliding carriages B. A sprocket-wheel, G', is mounted on a shaft, G'', journaled in vertically-movable standards above the wheel F'', so that the female sprocket-wheel G' can press down on the links of the chain G and hold the same in place on the sprocket-wheel F''. The upper journal-box, G', of the shaft G'' is pressed downward by spiral springs g, surrounding suitable standards, h, which spiral springs permit the female sprocket-wheel G' to give upward. The journal-boxes of the shaft G'' can be adjusted higher or lower, as may be desired, and as circumstances may require, by means of a key or wedge, g', passing through the frame, in which the journal-boxes G' rest, below the said journal-boxes. The movement of the chain G can rotate the female sprocket-wheel G'; but, if desired, a cog-wheel, g'', can be mounted on the shaft G'', and can engage with a cog-wheel, g', mounted on the shaft F', whereby the female sprocket-wheel G' will be operated from the shaft F'.

I have described one end of the machine only, as the ends are alike.

At the middle of the frame A two standards or upright frames, A'', are formed on each side, in each of which frames A'' a vertical right and

left hand screw-spindle, H, is journaled. This latter is provided at its upper end with a crank-handle, H', and with a beveled cog-wheel, H², engaging with a beveled cog-wheel, 5 H³, on a transverse shaft, I, journaled in the upper parts of the standards A², whereby if one screw-spindle H is turned by means of its crank-handle H' the opposite corresponding spindle H will be turned likewise. The 10 screw-spindles H pass through apertures j in the ends of gate-bars J, of which gate-bars all have a lug, J'. The gate-bars J are so arranged in relation to the vertical screw-spindles H that the left-hand threaded part passes 15 through the end of one gate-bar, and the right-hand threaded part passes through the end of the other gate-bar, as shown in Fig. 2, whereby when the said spindles are revolved the gate-bars will be separated or moved toward 20 each other. Between the gate-bars the die-holders K are held, each of which is provided with one or two apertures for receiving tubular dies L, which are preferably made tapering on the inner and outer sides. If desired, 25 the dies can be held in place in the die-holders by means of keys or wedges. The die-holders can be provided with one die or with two dies, as may be desired. The dies are of various sizes, as in an ordinary rolling-mill, 30 through which dies the bar is successively passed as it decreases in diameter. The die-holders K are to be clamped between the gate-bars J, by turning the spindles H more or less. The carriages B, for receiving the ends of the 35 bars, are provided with side grooves, b, for receiving longitudinal side projections, a, on the tracks A', so as to guide the carriage during its movement. The carriage is also provided on each side with a beveled lug, M, 40 adapted to strike against the handle D² and operate the same in the manner described hereinafter. The carriage is provided in its upper surface with a recess, N, for receiving the neck or narrow part of the end of the bar O, 45 which recess or groove N terminates at its inner end in an enlargement, P, for receiving the head O', formed on the end of the bar, which head rests against the shoulder formed at the union of the grooves N and P.

50 If desired, the carriage B can be provided with two grooves N, as shown in Fig. 5. A frame, Q, is held on the front part of the carriage, and in the said frame a shaft, Q', is journaled, which shaft is provided at one end 55 with a handle, Q², and crosses the grooves N, and on which shaft a cam, R, is rigidly mounted above each groove N, whereby, by turning the handle Q² up, the cams R will be pressed against the heads O' in the carriages, and will 60 thus firmly hold and lock the heads in the carriages. A rod, S, is held to slide in the frame Q parallel with the shaft Q', and is pressed in the direction toward the handle end of the shaft Q' by a spring, S', surrounding the said rod S. The projecting end of the rod S is formed or provided with a notch, into 65 which the handle Q² can be passed to hold it

in the raised position. The rod S is provided with a handle, S², for moving it in the direction of its length. The carriage B is provided 70 with a suitable shackle, T, to which the end of the chain G is fastened.

The operation is as follows: The bars to be drawn into shafting are cut the proper length, and the ends are heated and reduced for a sufficient length from the shoulder to the head O' to allow the thickest part of the bar to be drawn clear through the dies. The head is formed to pass through the dies and to fit into the recess or groove P in the carriages B, in 80 which they are locked by means of the cams R. Each end of the bar is held in a carriage. A die is placed on each end of the bar, and the die-holder containing the larger die is placed in the recess between the gate-bars J J. 85 The operator then turns the handle H' of one of the screw-spindles, whereby the gate-bars will be closed and will hold one of the dies firmly. The upper gate-bar is provided with a lug, J', to press down upon the die in the recess. The operator then pushes one of the handles D² in the direction of the arrow a', 90 whereby the lower ends of the levers D will be moved in the inverse direction of the arrow a', by which movements one of the clutch-wheels C³ will be pressed against and into its clutch-wheel C², and made to engage with the same, thereby rotating the beveled cog-wheels C' and E, the pinion E², and the wheel F, whereby the sprocket-wheel F² will be rotated 95 in such a manner as to draw the chain G in the inverse direction of the arrow a', by which means the carriage B will be moved in the same direction and will draw the bar through the die. When the carriage B at the other 100 end of the bar arrives at the handle-lever D², to the left of the standards A² in Fig. 1, the lugs M strike against the said handle-lever and throw it in the inverse direction of the arrow a', thereby moving the lower ends of the levers 105 D D' in the direction of the arrow a', and disengaging the cog-wheels C' at the right-hand end of the machine from the shaft. Then the die-holder K, mounted on the left-hand end of the bar O, is held between the gate-bars J by 110 turning the spindles H, and the levers D are thrown in the inverse direction of the arrow a', in order to engage the wheel C' at the left-hand end of the machine with the driving-shaft C. The left-hand chain G will then be 115 drawn in the direction of the arrow a' and will draw the bar O in the same direction, thereby drawing it through the left-hand die and again decreasing the diameter of the same. The bars can be drawn into shafts in one continuous operation in the manner above described. If 120 desired, two bars can be drawn at the same time. The machine need only be started, and when it has drawn the bar through a die it is 125 stopped automatically.

Having thus described my invention, I claim as new and desire to secure by Letters Patent—

1. The combination of the track A', the sliding carriages B B, having lugs M M, the shaft

- C, carrying loose beveled cog-wheels C', and its integral notched clutch-wheel C², the keyed sliding annularly-grooved clutch-wheel C³, the centrally-pivoted lever D, having bifurcated 5 prong d, the levers D', having upwardly-projecting handles D², and connecting with the ends of lever D by rods d' d', the transverse shaft F', having cog-wheel F, the sprocket-wheels F² F³, and the chain G, attached to said 10 carriages, as shown and described.
2. The combination of the two right and left cranked screw-spindles H H, the shafts I I, gearing with said spindles, and the gate-bars J J, having lugs J' and apertures j', as and for 15 the purpose specified.
3. A carriage, B, having a recess, N, terminating at its inner end in an enlargement,
- P, and forming shoulders, in combination with the shaft Q', crossing said recesses, having handle Q², and provided with cam R, as and 20 for the purpose set forth.
4. In a machine for drawing bars for shafting, the combination, with the standards A², of the screw-spindles H, the gate-bars J, the die-holders K, the beveled cog-wheels H² on 25 the spindles, the transverse shaft I, and the beveled cog-wheels H³ on the end of the same, substantially as herein shown and described, and for the purpose set forth.

JOHN S. GRIFFIN.
